UNITED STATES PATENT OFFICE.

HARRY SMITH WAINWRIGHT, OF ASHFORD, ENGLAND.

BLAST-PIPE FOR LOCOMOTIVES.

SPECIFICATION forming part of Letters Patent No. 737,798, dated September 1, 1903.

Application filed May 12, 1902. Renewed August 3, 1903. Serial No. 168,123. (No model.)

To all whom it may concern:

Be it known that I, HARRY SMITH WAINWRIGHT, a subject of the King of Great Britain and Ireland, residing at Ashford, in the county 5 of Kent, England, have invented Improvements in and Relating to Blast-Pipes for Locomotives, of which the following is a specification.

With the construction and arrangement of 10 blast-pipes heretofore commonly used in locomotive-engines the exhaust-steam usually issues from the blast-pipe in quick sharp blasts, especially when hauling heavy loads up inclines, with the result that the fire in the boiler- 15 furnace is caused to burn very irregularly and therefore uneconomically, and sparks or glowing particles are frequently ejected through the chimney to such an extent as to cause danger.

Now this invention has for its object, *inter alia*, so to construct a blast-pipe for a locomotive-engine that the flow of exhaust-steam therethrough shall be regulated or controlled in such a way that the steam will issue in a 20 smoother and more continuous manner than heretofore usual, so that it shall cause a more steady and uniform draft through the fire-tubes of the boiler and therefore a more steady, uniform, and economical combustion 25 of fuel in the fire-box and less liability of 30 ejecting sparks or glowing particles from the chimney than heretofore usual, and this without unduly baffling the steam and increasing the back pressure thereof in the engine-cylinders. 35 For this purpose the internal surface of a locomotive blast-pipe, according to this invention, instead of being made plain or smooth, as heretofore, is for the whole or a portion or portions of its length formed or 40 provided with ribs or projections, so arranged as to form one or more inclined or spirally-arranged grooves or channels, with the object of rendering the flow of steam through the blast-pipe more uniform and to facilitate 45 egress of steam by causing it to whirl or revolve. The ribs or projections may be formed in the metal of the blast-pipe itself or in or by one or more pieces of metal inserted within and fitting the blast-pipe. The grooves or 50 channels that are formed by and between the ribs or projections and which may resemble more or less the rifling of a gun may be of

uniform or varying pitch and the grooves or channels may be of uniform or varying depth, as may be desired. In the case of new blast-pipes the grooves or channels may conveniently be formed by casting. In the case of existing blast-pipes they may conveniently be formed by suitably coiling one or more lengths of metal wire or rod or one or more 60 lengths of strip metal to fit the interior of the blast-pipe and form the desired groove or channel or grooves or channels therein.

For the purpose of arresting or of assisting to arrest sparks or glowing particles that may 65 enter the smoke-box with the hot gases on their way to the chimney the blast-pipe may be formed with holes or passages, through which smoke and hot gases can freely pass into the blast-pipe, but not sparks or glowing 70 particles. The said holes or passages may advantageously be elongated and have a slight radially and outwardly upward inclination, so that their upper surfaces will aid in arresting and throwing down sparks or glowing 75 particles coming into contact therewith. The holes or passages may coincide with portions of the grooves or channels within the blast-pipe or they may be arranged in an upper portion of the blast-pipe, which may be made 80 longer than usual and have its upper portion either of uniform diameter or of gradually-increasing diameter above the conical portion of smallest diameter and be internally 85 grooved or not. The holes are preferably arranged spirally in the blast-pipe, with a view of facilitating the egress of steam by causing it to whirl or revolve. The blast-pipe, when thus adapted to arrest sparks, may be used in conjunction with a horizontal grid fixed in 90 the smoke-box above the level of the fire-tubes and formed with an aperture in which the upper open end of the blast-pipe is located or the upper perforated end of the blast-pipe may extend up to or beyond the base of the 95 chimney or up to or beyond the base of a petticoat or truncated cone supported below the chimney and used with or without a horizontal grid.

Figures 1 and 2 of the accompanying illustrations are vertical sections representing examples of blast-pipes provided with spiral channels according to this invention. Fig. 3 thereof is a plan corresponding to Fig.

2, and Fig. 4 is a vertical section of another example.

Fig. 1 shows a blast-pipe consisting of lower and upper truncated conical portions *a* and *b*, formed of one piece, the lower portion being of upwardly-decreasing diameter and the upper portion of upwardly-increasing diameter. The lower portion *a* has spiral ribs *c* cast in one with it for a portion of its length to form channels for the purpose hereinbefore mentioned. The upper portion *b* is formed with holes *d* through its wall. These holes have a radially and outwardly upward inclination, so that their upper surfaces *e* will aid in arresting and throwing down sparks or glowing particles coming into contact therewith. The partitions or ribs *f* between the holes *d* are, moreover, spiral and of the same pitch and direction as the ribs *c*. The upper portion *b* of the blast-pipe thus constitutes a spark-arresting device. In the case of existing blast-pipes rods bent to the shape of the ribs *c* may be secured to the interiors of the blast-pipes in lieu of casting ribs thereon.

Fig. 2 shows a blast-pipe comprising two portions *a* and *b*, such as shown in Fig. 1 except that the portion *a* is plainly conical internally and has secured in it, by means of brackets *g*, two metal strips *h* and *i*, which fit the interior of the blast-pipe and form the desired inclined or spiral channels. Fig. 3 is a top plan showing the arrangement of the strips *h* and *i*, whose spiral formation is produced by drawing them out. *j* and *k* are the top commencing edges of the two strips and *l* and *m* their internal peripheries. In this example also the spirals formed by the projections of the lower portion and by the holes or passages (and consequently by the partitions between the holes or passages) are in the same direction.

Fig. 4 shows a blast-pipe in which the lower and upper portions *a* and *b* are made separate from each other. The lower portion *a* has fine ribs *n* cast in one with it for the purpose hereinbefore mentioned, and the upper portion or spark-arresting device *b* fits in a socket *p*, formed by the upper end of the blast-pipe, and is composed of a frame comprising upper and lower rings *q* and *r* and notched or recessed bars *s* and rods or bars *t*, wound spirally around the frame and located in the notches or recesses of the bars *s*. The rods or bars *t* form extensions of the ribs *n*, and consequently the passages between the bars or rods *t* form continuations of the channels constituted by the ribs *n*. The upper portion *b* is shown as surrounding a chimney-cone *u* and fitting against a chimney-base *v*. In some cases a single spirally-arranged projection might be arranged in the lower portion of a blast-pipe instead of two or more and likewise a single spiral partition between the holes or passages of the upper portion.

It will be obvious that other changes in construction might be made without departing from the essential features of my invention.

What I claim is—

1. In a locomotive blast-pipe the combination of one or more spirally-arranged projections within the blast-pipe adapted to regulate the flow of exhaust-steam therethrough and a spark-arresting device formed with holes or openings separated by a partition or partitions of like spiral direction to said projection or projections. 75

2. A locomotive blast-pipe comprising a lower portion of upwardly-decreasing diameter and an upper portion which is in one piece with said lower portion and is formed with holes or passages adapted to allow smoke and hot gases to pass freely into the blast-pipe but not sparks or glowing particles. 80

3. A locomotive blast-pipe comprising lower and upper portions of which the lower portion is provided internally with one or more inclined or spirally-arranged projections adapted to regulate the flow of exhaust-steam therethrough and the upper portion is formed with holes or passages adapted to allow smoke 85 and hot gases to pass freely into the blast-pipe but not sparks or glowing particles. 90

4. A locomotive blast-pipe comprising a lower portion of upwardly-decreasing diameter and an upper portion which is in one piece with said lower portion and is formed with holes or passages adapted to allow smoke and hot gases to pass freely into the blast-pipe but not sparks or glowing particles, the upper surfaces of said holes or passages having a radially and outwardly upward inclination. 95 100

5. A locomotive blast-pipe comprising a lower portion of upwardly-decreasing diameter provided internally with one or more spirally-arranged projections adapted to regulate the flow of steam therethrough and an upper portion formed with holes or passages adapted to allow smoke and hot gases to pass freely into the blast-pipe but not sparks or 110 glowing particles, said holes or passages being separated by a partition or partitions of like spiral direction to said projection or projections. 105

6. A locomotive blast-pipe consisting of lower and upper portions formed in one piece, of which the lower portion is of gradually-decreasing diameter in an upward direction and is provided with a projection or projections adapted to cause exhaust-steam to whirl or 115 revolve in passing therethrough, and the upper portion is formed with holes or passages adapted to allow smoke and hot gases to pass freely into the blast-pipe but not sparks or 120 glowing particles. 125

7. A locomotive blast-pipe consisting of lower and upper portions formed in one piece, of which the lower portion is of gradually-decreasing diameter in an upward direction and is provided with a projection or projections 130 adapted to cause exhaust-steam to whirl or revolve in a certain direction in passing therethrough, and the upper portion is formed with holes or passages which are arranged to

form a spiral or spirals having the said direction and are adapted to allow smoke and hot gases to pass freely into the blast-pipe but not sparks or glowing particles.

- 5 8. A locomotive blast-pipe consisting of a lower portion which is of upwardly gradually decreasing diameter and is provided with one or more projections arranged in a spiral or spirals and adapted to regulate the passage of 50
 10 exhaust-steam therethrough and an upper portion which is of upwardly gradually increasing diameter and is formed with holes or passages which are arranged in a spiral or spirals having the same direction as the afore-
 15 said spiral or spirals and are adapted to allow smoke and hot gases to pass freely into the blast-pipe but not sparks or glowing particles.
 9. In a locomotive-engine, the combination of a chimney-base, and a blast-pipe comprising 55
 20 a lower portion of upwardly-decreasing diameter and provided with a projection or projections arranged in a spiral or spirals and adapted to regulate the passage of exhaust-steam therethrough, and an upper portion
 25 which is of upwardly-increasing diameter, extends to said chimney-base, and is formed with holes or passages which are arranged in a spiral or spirals having the same direction as the aforesaid spiral or spirals and are adapted to allow smoke and hot gases to pass freely 60
 30 into the blast-pipe but not sparks or glowing particles.
 10. In a locomotive-engine, the combination of a chimney-base, a chimney-cone, and 65
 35 a blast-pipe comprising a lower portion of upwardly-decreasing diameter and provided with a projection or projections arranged in a spiral or spirals and adapted to regulate the passage of exhaust-steam therethrough, and
 40 an upper portion which is of upwardly-increasing diameter, surrounds said chimney-cone, extends to said chimney-base, and is formed with holes or passages which are arranged in a spiral or spirals having the same 70
 45 direction as the aforesaid spiral or spirals and

are adapted to allow smoke and hot gases to pass freely into the blast-pipe but not sparks or glowing particles.

11. A locomotive blast-pipe, comprising a lower portion, means carried thereby for regulating the flow of exhaust therethrough, and an upper portion formed with spirally-arranged openings, substantially as described. 75

12. A locomotive blast-pipe, comprising a lower portion, spirally-arranged members 55
 therein adapted to regulate the flow of exhaust therethrough, and an upper portion formed with spirally-arranged openings, substantially as described.

13. A locomotive blast-pipe, comprising 60
 lower and upper portions made in one piece, and spirally-arranged projections carried by the inner side of said lower portion, said upper portion having openings adapted to prevent the entry of sparks therethrough but to 65 allow the free passage of smoke into the blast-pipe, substantially as described.

14. A locomotive blast-pipe, comprising lower and upper portions made in one piece, and spirally-arranged projections carried by 70
 the inner side of the said lower portion, said upper portion having spirally-arranged openings adapted to prevent the entry of sparks therethrough but to allow the free passage of smoke into the blast-pipe, substantially as described. 75

15. A locomotive blast-pipe, comprising lower and upper portions made in one piece, and spirally-arranged projections carried by 80
 the inner side of said lower portion, said upper portion having holes or passages which are arranged in a spiral or spirals having the same direction as the aforesaid spiral projections, substantially as described.

Signed at Charing Cross Hotel, London, 85
